UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,423, dated July 3, 1888.

Application filed March 17, 1888. Serial No. 267,570. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

In the accompanying photographs, Figure 1 shows my design in a single row; Fig. 2, the same in two rows, and Fig. 3 the same in multiple rows.

Similar letters of reference indicate like parts.

My design consists in the rectangular elevation A, having beveled or inclined sides B. Upon the face of said elevation A appears a

rectangular pyramid, H, having four outwardly-curved or convex faces, C D E F. The area of the base of pyramid H is smaller than the area of the face of the elevation A, and around the base of said pyramid appears a flat portion, G, of said face. The sides of said pyramid project from said face at a sharp or plainly-marked angle.

I claim—

The design for surface ornamentation of walls, &c., substantially as herein shown and described.

FREDERICK KOSKUL.
